UNITED STATES PATENT OFFICE.

JOHN SCANLAN, OF CHICAGO, ILLINOIS.

STREET-RAILWAY TRACK.

SPECIFICATION forming part of Letters Patent No. 719,512, dated February 3, 1903.

Application filed November 21, 1902. Serial No. 132,229. (No model.)

To all whom it may concern:

Be it known that I, JOHN SCANLAN, a citizen of the United States, residing in the city of Chicago, county of Cook, and State of Illinois, have invented a new and useful Improvement in Street-Railway Tracks, of which the following is a specification.

It is a common practice in street-railway construction to employ a rail of such cross-section that the track is useful not only for the railway-cars, but also for traffic-wagons and other vehicles. In the ordinary construction the rails are provided with flanges extending inwardly toward the center of the track, the upper surfaces of the flanges being at a sufficient distance below the level of the tread of the rail to allow for the flange of the car-wheel and permit the tread of the car-wheel to rest upon the tread of the rail. As a result of this difference of level between the rail-flange and rail-tread a wall is formed on each rail, and in the present manner of laying the track the rail-flanges are both inside of the said walls—that is to say, toward the center of the track. These walls form an impediment to the wagon-wheels when an attempt is made to turn out of the track, and in the case of heavily-loaded wagons this impediment is a serious one, for the rear wheels tend to remain in the track for a considerable distance after the front wheels have left it, and if while the rear wheels are thus sliding along at an angle with the track they come into contact with a stone or other obstacle 35 there is a great danger that the wheel thus interfered with will give way. Frequent delays in traffic are due to this cause.

It is the object of my present invention to construct a track which will afford trackway 40 for wagons and other vehicles, as well as railway-cars, and which will facilitate the turning out of such wagons without decreasing the security of the cars upon the rails. I attain this object by the construction shown in 45 the accompanying drawings, in which—

Figure 1 is a plan view of a track embodying my invention. Fig. 2 is a sectional view thereof, taken on the line 2 2, Fig. 1, and looking in the direction of the arrows. Fig. 3 is 50 a transverse sectional view showing the arrangement of the rails in a double-track road

and the different positions which a car and a wagon would assume thereon.

In the use of the words "left" and "right" hereinafter it is considered that the view is 55 taken in the direction of the arrows on the line 2 2, Fig. 1.

Similar characters refer to similar parts throughout the several views.

The rail-flange 1 extends laterally from 60 the rail-tread 2, but has its upper surface at a less height than the upper surface of said tread, the wall 3 being thereby formed at the junction of said flange and tread. The foot 4 of the rail is mounted upon the cross-ties 65 5 in the usual manner. The surface of the pavement 6 is substantially on a level with the top of the rails. In my track construction instead of having the flanges 1 both extending toward the center of the track the 70 rails are so laid that the flange of rail *a* at the left, Fig. 2, extends toward the center of the track, but the flange of rail *b* at the right extends outwardly—that is to say, both flanges of the pair of rails extend in the same 75 direction.

By my construction when the wheels of a wagon are in position upon the flanges 1, as shown in Fig. 3, the wagon may easily turn out to the right, or in a direction away from 80 the rail-treads 2, the walls 3 not being in a position to interfere. If it is desired to turn out to the left, the wagon will first be driven a short distance to the right, and when the wheels have left the rails the wagon will be 85 turned toward the left, when the wheels will be found to cross the rails without difficulty on account of the fact that they then cross the tracks more nearly at right angles thereto.

The car-wheel flanges commonly engage 90 the rails on the inner edge of the rail-tread, as shown at the left portion of Fig. 3, and in order to provide room for the wheel-flange a space 7 is left between the tread 1 of the right rail *b* and the adjacent portion of the 95 pavement 6. When stone paving-blocks are used, as shown in the drawings, a spacing-block 8 is located between the inner surface of rail *b* and the adjacent paving-block, thereby effectually preventing the too close 100 approach of said block to the rail.

In constructing a double-track road the

rails are arranged as shown in Fig. 3, the flanges on rails *a* and *b* on the left track extending toward the left and the flanges upon the rails *c* and *d* on the right extending toward the right. By this arrangement a wagon can always turn most readily outward in a direction away from the track at the driver's left.

What I claim as new, and desire to secure by Letters Patent, is—

1. A street-railway track having the rail-flanges both extending laterally in the same direction.
2. A double street-railway track, each track consisting of a pair of flanged rails having their flanges extending away from the rails of the other track.
3. In a street-railway, a pair of rails each having a tread and a flange, the flange of one extending toward the second rail but the flange of the said second rail extending away from the flange of the first-mentioned rail.
4. In a street-railway track, a pair of rails, each having a flange and a tread, the flange of only one of said rails extending away from the other rail of the pair; in combination with a pavement and a wheel-flange space between

said pavement and the tread of the rail having the outwardly-extending flange.

5. In a street-railway track, the combination of rails each having a flange and a tread, the flanges of said rails extending both in the same direction; a pavement; and a distance-piece between one of said rails and the inter-rail portion of the pavement for retaining the inter-rail pavement at a distance from the tread of one of said rails, thereby affording a space between said pavement and said rail-tread for the flange of a car-wheel.

6. In a street-railway track a pair of rails, a single tread upon each of said rails for supporting a car-wheel; a single flange upon each of said rails for supporting a wagon-wheel, said flanges both extending in the same direction from said pair of rails; a pavement; a wheel-flange space located between said rails and adjacent to one of the rail-treads; and a distance-piece for preventing the pavement from closing said wheel-flange space.

Correction in Letters Patent No. 719,512.

It is hereby certified that in Letters Patent No. 719,512, granted February 3, 1903, upon the application of John Scanlon, of Chicago, Illinois, for an improvement in "Street-Railway Tracks," an error appears in the printed specification requiring correction, as follows: In line 27, page 2, the omitted letters "pa" should be inserted, making the imperfect word read *space*; and that the said Letters Patent should be read with this correction therein that the same may conform to the record of the case in the Patent Office.

Signed and sealed this 24th day of February, A. D., 1903.

[SEAL.]

F. I. ALLEN,
Commissioner of Patents.

rails are arranged as shown in Fig. 3, the flanges on rails *a* and *b* on the left track extending toward the left and the flanges upon the rails *c* and *d* on the right extending toward the right. By this arrangement a wagon can always turn most readily outward in a direction away from the track at the driver's left.

What I claim as new, and desire to secure by Letters Patent, is—

1. A street-railway track having the rail-flanges both extending laterally in the same direction.
2. A double street-railway track, each track consisting of a pair of flanged rails having their flanges extending away from the rails of the other track.
3. In a street-railway, a pair of rails each having a tread and a flange, the flange of one extending toward the second rail but the flange of the said second rail extending away from the flange of the first-mentioned rail.
4. In a street-railway track, a pair of rails, each having a flange and a tread, the flange of only one of said rails extending away from the other rail of the pair; in combination with a pavement and a wheel-flange space between

said pavement and the tread of the rail having the outwardly-extending flange.

5. In a street-railway track, the combination of rails each having a flange and a tread, the flanges of said rails extending both in the same direction; a pavement; and a distance-piece between one of said rails and the inter-rail portion of the pavement for retaining the inter-rail pavement at a distance from the tread of one of said rails, thereby affording a space between said pavement and said rail-tread for the flange of a car-wheel.

6. In a street-railway track a pair of rails, a single tread upon each of said rails for supporting a car-wheel; a single flange upon each of said rails for supporting a wagon-wheel, said flanges both extending in the same direction from said pair of rails; a pavement; a wheel-flange space located between said rails and adjacent to one of the rail-treads; and a distance-piece for preventing the pavement from closing said wheel-flange space.
